UNITED STATES PATENT OFFICE.

LEANDER A. COGSWELL, OF MANCHESTER, NEW HAMPSHIRE, ASSIGNOR TO LACENE MANUFACTURING COMPANY, OF MANCHESTER, NEW HAMPSHIRE, A CORPORATION OF MAINE.

AUTOMATIC TOP-LIFT GRADING AND DISTRIBUTING MACHINE.

Application filed August 20, 1921. Serial No. 494 009.

My present invention is an improved and automatic machine for feeling, detecting and distinguishing successive blanks of material of varying thicknesses, sizes, dimensions or the like, and to sort or distribute the same automatically into corresponding piles, groups or receptacles. There are two species of grading means (reverting to the terminology established in this art by the Nichols 5 patents) herein disclosed and contained in the more complete embodiment of my invention, viz, skiving to the predetermined thickness measurement and distributing according to the same predetermined thickness measurement. The machine is particularly intended for operation upon leather blanks, such for example as soles, taps, heel lifts and the like, wherein successive blanks fed into the machine vary in thickness, grade, or "irons" and 10 15 20 25 30 35 40 45 50 55 60 65 70 75 80 85 90 95 100

I provide automatic mechanism which will successively detect and determine the particular grade, thickness or iron of the blank and then distribute the blanks, delivering all the blanks of the same thickness into the same position, pile or receptacle. This feature of the invention is an improvement upon the grading and distributing machine illustrated in the prior patent to Elmer P. Nichols, No. 1,281,639, issued October 15, 1918. Preferably I combine with the feeler and detecting, and sorting and distributing mechanisms, means to skive or split the leather blank to a predetermined thickness throughout its length, this feature constituting an evening operation similar to that illustrated in the wellknown Nichols evening and grading machine, to insure the uniform thickness of each blank distributed to its predetermined point, pile or receptacle. In carrying out the present feature of the evening or splitting of the blanks, according to the desired thickness, determined by the detecting mechanism, I prefer to utilize a single bevel knife, such as is illustrated in Nichols Patent 1,205,104, dated November 14, 1916, this feature having special advantages in machines of this kind, as explained and set forth in said patent. Important features of the present invention consist in the mechanism for automatically handling, separating and feeding into the machine blanks from a stack or pile. This feature is of special importance, since the han-

dling of leather blanks of varying thicknesses, different quality, and the like, is extremely difficult. Leather blanks for shoe soles, taps, heels, etc., are of varying thicknesses and are frequently liable to be or to become curled or distorted, and the feeding mechanism must have a capacity to separate the blanks successively, irrespective of thickness, hardness or softness of the leather, and to handle such blanks with curled up edges and the like. I provide feeding mechanism which will automatically separate and feed an extremely thin blank from an adjacent thin blank, as well as an extremely thick blank from the stack, although the combined thicknesses of two of the thinnest blanks, may approximately equal, for example, that of the thickest blank to be operated upon. These advantages are of great importance in a machine of this kind, since the mechanism must be capable of handling all kinds, grades and qualities of leather before the blanks are skived, straightened or otherwise operated upon.

A further feature of importance is the automatic distributing mechanism, which operates with great speed and yet gives ample time for the blanks, after they have passed through the skiving mechanism, to be sorted and distributed to the different piles or receptacles adapted to receive each graded blank. In order to obtain the maximum capacity of the machine and permit the feeding mechanism to work speedily, I arrange the distributing mechanism to operate in such timed relation that the feeding in action of a successive blank or blanks is being carried out before the distributing is completed. In other words the distributing mechanism is set and a blank which has been operated upon is being conducted to its predetermined point or receptacle while a succeeding blank is being or has been fed into and is traversing the machine, thus giving ample time for the sorting and distributing action without delaying the automatic feeding and the working of the machine to its capacity.

Various means have been heretofore proposed (and patented) of "grading" cut stock, by which is meant operating on blanks in response to their gaging or detecting as to thickness or usefully perpetuating or utilizing the

grade detection, such as stamping, skiving, compressing, distributing, and I have herein shown how a series of such means may be coupled up so as to be adjusted or set dissimultaneously and released (or restored to be reset for the next blank), dissimultaneously either or both, in response to one gaging (i. e., detecting or feeling) operation. I have presented the subject in connection with a series 10 of two of such means, viz, skiving and distributing, but it will be understood that I am not limited to this series or selection of such blank-operating means or grading means as my invention is broadly new in connection with any series and I intend so to claim it. The object, as to this feature, is to speed up the output of the machine. The invention, in other words, consists in detecting the grade of a succeeding blank and transmitting its grade to the setting mechanism as soon as the first operating or grading means has completed or nearly completed its operation on a preceding blank and before the next 20 operating or grading means has operated on said preceding blank, thereby enabling a plurality of blanks to be going through the machine simultaneously.

A still further feature of broad novelty and importance, which combines with the foregoing to facilitate speed, accuracy and general efficiency, is the arrangement for automatically and positively separating, opening or spreading apart the feeding-in rolls just as and while the blank is entering between them. This permits the use of smooth rolls, saves injuring the blanks, improves the delicacy and accuracy of measuring or detecting, permits higher speed of blank movement, permits uniformity of operation and absence 30 of shock and materially reduces the power required. As soon as the blank has been fed forward to the desired position between the separated rolls, said rolls are instantly closed upon the opposite sides of the blank, thereby 40 engaging the latter with the minimum grip and with no pounding or wedging action such as was invariably the case with the old construction in which the separation of the rolls was accomplished by forcibly butting the 45 blank endwise against the bite of the contacting rolls. To insure quick riding up on the blank end, it was found necessary to employ expensive fluted or corrugated rolls, so that not only were the blanks apt to be bruised 50 and bent up at their front ends but they were marred or indented and damaged by the corrugations of the rolls. All these disadvantages are eliminated by my present invention. This feature and the corresponding feature 55 of positively opening the gate, I believe to be broadly new and therefore I intend my claims therefor to be correspondingly construed.

In a machine of the present type, wherein 60 these feeding rolls are employed to gage the

thickness of the stock, and for setting the skiving and distributing mechanism, as well as for operating the indicators, where an indicator is employed, I obtain a much more accurate measuring action through the instrumentality of smooth surfaced rolls, than where corrugated rollers are employed. 70

A further feature consists in the provision of means, also automatic, to lift and raise the gate in timed relation with the feeding in 75 action so that the feeding devices will be enabled to select, separate and move forwardly a blank freely and without interruption, directly into the feeding and gaging rolls, which have also been opened to receive the 80 blank. It will be appreciated that, when soft or spongy leather is being operated upon, or other flexible material, the material itself might be insufficient to pry or force open the gate or rolls, thereby becoming wedged, 85 jammed or the like and otherwise delaying and interrupting the feeding in action and the operation of the machine. I consider that my arrangement of providing positive means which will lift and open both the gate and 90 the feeding rolls, is of great importance, this action being timed to cooperate with the automatic feeding devices as above briefly explained. 95

While it is feasible to attach marking or indicating devices to the machine to stamp and mark or permanently impress, or if desired, to visually indicate, the grades and sizes of material being operated upon by the machine, yet with the automatic distributing 100 feature, such indicating and stamping is entirely unnecessary, because the blanks are all sorted and distributed automatically, and delivered into a receptacle. In my present machine I provide means giving a comparatively wide scope or range to the material being operated upon. When leather blanks, for example, are being put through the machine, a range of sizes of seven or eight different grades can be handled advantageously, 105 this being as large a variation in sizes as it is usually necessary to operate on. Preferably eight receptacles are provided, each positioned with regard to the delivery device, so that as a blank is fed into the machine, and 110 its grade determined, the receptacle to which it will be delivered is likewise predetermined, and therefore all the blanks of the same grade are delivered to the same receptacle. No marking and indicating is therefore requisite 115 and of course no subsequent sorting, piling and distributing is required. In this sorting and delivering I prefer to utilize a chute movable to conduct each predetermined blank to its predetermined receptacle, such a chute 120 being movable and set by the machine when the thickness of the blank has been determined by the detecting rolls or other devices and when an evening knife is employed, the blank is necessarily evened or split to the 125 130

predetermined gage for which the gaging mechanism and chute have also been set by the stock itself. Thus errors are absolutely eliminated and the machine is positive in its 5 setting and distributing action. As the movable chute is swung with considerable speed when the machine is operating at capacity, I provide means to hold, lock and steady the chute in any position to which it may have 10 been moved and set, until the blank responsible for such setting and moving has been delivered to its receptacle.

As some appreciable time is required for this delivery, I provide mechanism which 15 will hold the chute thus fixed, while permitting the mechanism operating the chute to determine the distribution of the succeeding blank to be moved, only releasing the position to which the chute has been moved for 20 the preceding blank when the succeeding blank has practically traversed the machine, thereby affording a substantially long and ample length of time for the distributing action.

25 In the preferred embodiment of the machine and as shown in the accompanying drawings, wherein I prefer to utilize a skiving knife, preferably a single bevel knife as above noted, I have also employed means to 30 maintain the blank in a smooth, level or substantially level, and straight horizontal position or condition. As is well known in the art of skiving leather, the action of a skiving knife thereon necessarily results in curling 35 or tending to curl, distort or disaline, the leather blank, and heretofore this has been one of the difficulties incident to the leather skiving operation. In my present machine I have applied means operating on the leather 40 after the skiving action, and preferably co-operating therewith to smooth out the blank and prevent it from curling or other distortion due to the cutting, skiving and trimming action. This feature is most important when 45 treating leather blanks such as soles, taps, heels, etc., because the stock should be thus delivered from the machine in condition for instant use in the shoe manufacturing processes. I carry out this feature by applying 50 a pair of rollers in the line of travel of the stock and in position to act thereon after the skiving action or simultaneously with the completion of an operation of such skiving action. These rolls furthermore serve to 55 smooth, condense and stiffen and strengthen the stock, particularly when soft or spongy leather is employed. These rolls may (if desired, although not ordinarily) be set to act with considerable tension, thus consolidating 60 the fiber and texture of the stock while passing therethrough, and thus levelling, smoothing and ironing out the same, heated rolls for this purpose being employed if desired and thus each blank is effectually smoothed out, 65 condensed, and its wearing qualities im-

proved. Furthermore, by acting upon the leather blank after skiving, the blank is ready for incorporation in a shoe, instead of being first passed through other straightening, condensing or compressing machines, as has heretofore been necessary. These rolls act as a positive means to pull the blank from the skiving devices, insuring the continuous speed of feeding and also a positive delivery of the blank to the distributing chute. 75

The automatic feeding device has a further provision permitting a wide range of adjustment for the handling of blanks from the largest size men's soles, 12 to 14 inches in length, to children's soles, and even to heel 80 blanks and lifts, three or four inches in length. In order to facilitate the operation of the machine on the latter and similar types of materials, I have provided novel means whereby the range of adjustment is sufficient 85 to enable one machine to handle all these varying lengths and for this purpose I have devised means permitting the reciprocating feeding member to feed or force the blank into the first rolls, i. e., the detecting and 90 feeding rolls, back of the gate. In order to accomplish this purpose I have provided mechanism permitting the reciprocating member to actually pass through or beyond the gate in the blank feeding action, to thus 95 positively force the smallest heel blank into the feeding grip of the rolls.

Further advantages, novel combinations of parts, important improvements, and constructional features, will be hereinafter more 100 fully pointed out and claimed.

Referring to the drawings illustrating a preferred embodiment of the invention,

Fig. 1 is a plan view of my machine;

Fig. 2 is a side view, partially in cross 105 section;

Fig. 3 is a longitudinal cross-sectional view on the line 3—3, Fig. 1;

Fig. 4 is a cross-sectional view on the line 110 4—4 of Fig. 1;

Fig. 5 is a front view partly in section on the line 5—5 of Fig. 1;

Fig. 6 is a fragmentary view, partly in cross-section taken just back of the ratchet plate and looking to the right, of the pawl and ratchet mechanism; 115

Fig. 7 is a horizontal fragmentary view illustrating the mechanism for actuating the distributing chute;

Fig. 8 being a detailed view of the rack bar 120 and sleeve shown in Fig. 7;

Fig. 9 is a fragmentary plan view of the feed hopper devices;

Fig. 10 being a view, partly in cross-section, on the line 10—10 of Fig. 9; 125

Figs. 11 and 12 are views similar respectively to Figs. 9 and 10 but of a modified construction;

Figs. 11, 12 and 13 also show the blank 130 guides and accompanying mechanism, Fig.

13 being a horizontal cross-sectional view taken at about the point of the broken top of the hopper, Fig. 2;

Fig. 14 is a fragmentary cross-sectional view of the lever and cam construction acting to separate the feeding and gauging rolls;

Fig. 15 is a detailed view, partly in cross-section, showing the tripping mechanism;

Figs. 16 and 17 and 18 are details of a modified form of blank separating and feeding device, Fig. 16 being a central vertical section of a fragmentary portion thereof, Fig. 17 being a top plan view of the blank engaging reciprocator and Fig. 18 being a bottom plan view thereof;

Fig. 19 is a fragmentary view and side elevation of a portion of the gate opening means; and

Fig. 20 is a fragmentary view in section showing, in side elevation, the distributor unlocking trip.

In the more complete embodiment of my invention as herein shown there are six principal elements or groups, viz, a hopper or blank supplying mechanism for supplying and feeding the blanks one by one to the feeling or detecting mechanism, said feeling or detecting mechanism which transmits its determinations to a distributor, a setter or setting mechanism which adjusts the distributor as well as the skiving means, the blank being passed along to an evening or skiving mechanism from which it is taken by a delivering mechanism and delivered to the distributor, said distributor having meanwhile been adjusted and set by the distributor adjusting and setting mechanism. In carrying out my invention I have availed myself of the principal parts of one type of the Nichols evening and grading machine, although it will be understood that I am not limited to this mechanism and that for instance the evening feature may be omitted and that my invention in its principal objects may be carried out in connection with various other grading mechanisms or evening and grading mechanisms.

The feed roll 1 and chain 2, detector or feeler plate 3 (and a detector or feeler roll 4 in connection therewith to facilitate the movement of the blanks) above which is a yoke 5 engaged adjacent its opposite ends by bell crank levers 6 and 7 held under tension at their upper ends by an equalizer spring 8, and said yoke carrying vertical feelers or feeler posts or detectors 9 and 10 connected at 11 to arms 12 extending from a rock shaft 13, may be and are in general type the same as in the Nichols Patent, 1,046,213, dated Dec. 3, 1912. The feeling or detecting and transmitting and adjusting mechanisms of my present machine are substantially the same, at least in general type, as in said patent and accordingly I have not undertaken herein to show all the details thereof. As herein

shown a crank 14 is on the right hand end, Fig. 5, of rock shaft 13 and connects pivotally at 15, Fig. 7, to a pivotally mounted sector 16, having on its under side teeth 17 (corresponding to the teeth 34 of said patent) 70 and at its opposite end is provided with a segmental rack 19 meshing with the pinion 20, whose shaft 21 carries at its upper end a similar pinion 22 in engagement with a sliding rack bar 23 mounted in the cross head 24, 75 see Fig. 3, and provided on its under side and opposite ends with depending inclines or cam stops 25 to cooperate with reverse inclines 26 fixed on the journal boxes or bearings 27 which carry the opposite ends of the pressure gage roll 28, all operating to control the splitting as adjusted in response to the adjusting mechanism as in said Patent 1,046,213. Beneath the upper gage or feed roll 28 is a lower feed roll 29 held yieldingly 85 upward by springs 30 to cooperate with the skiving or splitting knife 31 (shown as the knife construction of Patent 1,205,104 previously mentioned). The work travels over a bed 32 beneath a shoe or presser plate 33 90 pivotally supported yieldingly at 34 from a bracket 35. The drive shaft 36, Fig. 2, drives a sprocket chain 37 and sprocket wheel 38 on whose shaft 39 is a pinion 40 meshing with a gear 41 whose shaft 42 carries the 95 sprocket wheel 43 Fig. 3 which drives the sprocket chain 2 which in turn drives the front feed roll 1. The shaft 36 also carries a gear 44 in mesh with a pinion 45 which engages a gear 46 on the near end, Figs. 1 and 100 2, of the upper out-feed roll or pressure roll 28. On its farther end, Figs. 1 and 2, the main shaft 36 has a pinion 47 which drives the gear 48 of the lower out-feed roll 29.

I have illustrated my invention in connection with the foregoing mechanism which is or may be in general type substantially the same as in the Nichols Patent No. 1,046,213 before mentioned, but it will be understood that although I have utilized much of this 105 old mechanism, the relations and combinations in which it is used are new and enable me to produce the automatic feeding, gaging, evening and distributing as will be understood in the course of the following description, and enable me to accomplish the final result with speed and accuracy.

For convenience, and preferably, the feeding is accomplished from a stack, the blanks 49 being herein shown as deposited between 110 a stationary but adjustable front wall 50 and a fixed rear wall 51. The latter is shown in detail in Figs. 1, 2, 9-13. This wall 51 carries lateral vertical guides 52 held in true vertical parallelism by lateral members 53 fitting transverse grooves 54 in the front of the upright 51, and they are simultaneously moved toward or from each other by a right and left hand screw 55 mounted to turn in a fixed bracket 56 and carrying opposite nuts 115 120 125 130

or arms 57 extending thereto from the respective guide uprights 52, so that when the guide screw 55 is turned over to the left, Fig. 2 and Fig. 13, the guides 52 will be separated to fit 5 wider stock than previously might have been in the hopper. My machine is especially constructed to handle thin and difficult work. One difficulty with the previous machine (Patent No. 1,281,639) was that it might feed 10 two pieces of work at the same time, particularly such as thin top lifts, and accordingly to prevent this I have mounted on the lower end of the rear of the hopper blank retarders, one form being shown in Figs. 9 and 10 15 and another form in Figs. 11 and 12. Referring to Figs. 9 and 10 it will be seen that a bar 58 is mounted to move up and down in a way 59 provided at the rear of the wall 51, said bar being held down yieldingly by a spring 20 60 and provided with a beveled foot 61 in position to be engaged by the lower pieces of work, such as top lifts. Thus when a top lift is moved rearward in the machine by the feeding mechanism it moves against the foot 25 61 with only slight resistance at the very bottom edge of said foot but if a second or third top lift should be accidentally moved along frictionally by and with the bottommost top lift said upper lifts will engage forcibly 30 against the upper portion of the foot and will thereby be held back as the only way the said upper top lifts can get through is against the frictional resistance of the foot 61 and the resistance of the spring 60. This form of 35 retarder is especially adapted to very small and thin top lifts. The form shown in Figs. 11 and 12 consists of two depending deflectors 62 pivoted at 63 in the lower ends of the guides 53 and normally held downward by 40 springs 64 but otherwise acting very much the same as the foot 61. Opposite these deflectors or at the rear side of the front wall 50 I cut away said wall to provide a beveled recess 65 which enables the lower top lifts to drop 45 down more readily to position for being fed into the machine when the reciprocating device returns after having fed forward the bottommost blank. If this wall were straight without said recess there would be a frictional resistance which might result in the 50 next blank remaining stuck or not dropping into feeding position. In Figs. 1 and 3 I have shown a feed hook or work projector in the form of a hook 66 held under upward 55 tendency by a spring 67 and pivoted at 68 to an adjustable plate 69 engaged by a yielding stud 70 held in a carrier 71 at the upper end of a reciprocating post 72, said carrier being mounted to reciprocate in ways 73 in the top 60 of the table 74 which carries the hopper and blank engaging mechanism thus far described. As my machine is especially arranged to handle very small pieces of stock such as small sizes of heel lifts for instance, 65 it is necessary that the reciprocator or work

projector 66 shall move very close to the rolls 1 and 4, so that the bevel or inclination of said projector between its pivot and the engaging shoulder or hook has to be quite steep. In view of this fact, together with the necessity for handling curled and often very thin pieces of stock I have provided at each side of the raceway 73 stationary inclines 75 which serve to hold the rear edge of even badly curled pieces of stock in such a position 75 that the hook is sure to engage said pieces sufficiently to project them. In Figs. 16-18 I have shown a form of projector which can handle still smaller pieces of stock (because it can go closer to the feed and detecting 80 rolls). This form consists of a projector plate 76 having a short bevel 77 and mounted on an adjacent plate 78 substantially the same as plate 69. Preferably this plate 76 is roughened or knurled at its top 79 to aid in bringing back the next or second top lift when the first has just been fed or projected. The projector 66 and connected parts are actuated by a rotary shaft 80 whose crank 81 is connected 85 by a link 82 to the reciprocating post 72, said rotary shaft being actuated by a gear 83 on its outer end, see Figs. 1 and 2, meshing with an idler 84 in engagement with a clutch gear 85 normally idle but actuated at the proper moment to engage a continuously rotating 90 clutch part 86 fast on the outer end of the feed roll shaft which carries the roll 1. As before emphasized, my invention is specially adapted to handle difficult stock (such 100 as curled and thin and small pieces) and accordingly one of the features on which I place special emphasis is the provision of means for separating the ingoing rolls 1 and 4 of the detecting mechanism and raising the gate 87 (which, however, in my machine performs more the function of a trip than of a gate proper), so that even the thinnest or most refractory stock is sure to get in place between the detector rolls. Without this feature such stock would be apt to turn up 105 against the gate or wedge or crumple against the rolls, but by this provision the gate is raised just before the blank reaches it and then the blank is fed onward into position beneath the then separated rolls which immediately come down on it in the performance of their feeler or detecting operation and at the same time the gate or trip 87 falls on the top surface of the stock where it rests until the stock passes out from under it. The gate is 110 lifted by a cam lever 88 whose free end 89 loosely engages the arm 90 of the gate, said cam lever being pivotally connected at 91 to the under side of the table and having its cam portion in position to be engaged by the 115 swinging end 92 of the crank 81 fast on the inner end of the shaft 80, see Figs. 2 and 19 as before described. The upper roll 4 is lifted by the engagement of a cam 93 mounted on the shaft 80, with a tripping shoulder 94 of 120 125 130

a yoke 95, see Figs. 3, 5 and 14, pivoted to the frame at 96 and whose opposite ends 97 project under the opposite ends of the upper roll 4 in position to lift said roll under the actuation of the cam 93. The top lift or piece of stock is carried along from the feeler or detecting mechanism by the chain 2 to the outgoing rolls 28, 29 where it is evened by the skiving knife 31 in accordance with the thinness measurement or detection to which said rolls have been set, and the evened or skived blank is then instantly grabbed by two delivery rolls 98 and 99, Figs. 1, 2 and 3, the former being driven by a pinion 100, Fig. 2, and 15 idler 101 which is in turn driven by the pinion 41.

These rolls 98, 99 have several important and striking functions but their main purpose is to insure delivery of the blank and also to 20 make sure of a quick delivery. The main purpose of an automatic feeding and distributing machine is to save labor, and therefore such a machine, to be successful, must do the work quicker than skilled hand labor. Hence the 25 parts of my machine are so coordinated that they hurry the blank into the machine and hurry it out of the machine with no liability of the blanks sticking or pausing or being delayed at any point. Therefore the rolls 98, 30 99 are provided to seize the blank and propel it rapidly forward into a chute 102 provided for it for distributing the successive blanks to different receptacles according to their grade. A second function of these rolls which 35 98, 99 also conduces to speed is due to the arrangement by means of which they positively and instantly start the blank feeding mechanism and means for raising the gate and separating the ingoing rolls the instant that the outgoing 0 blank has proceeded far enough to be sure of being distributed before the chute 102 changes to the next position. As herein shown this is accomplished by providing a cam 103, see Fig. 3, on or as a part of the roll 15 99 to engage an arm 104 on a rock shaft 105 provided at its outer end, Fig. 2, with a rocker arm 106 connected by a link 107 to a trigger or actuator 108 pivoted at 109 on an adjacent stationary part of the machine and depending to 20 engage and actuate the free end 110 of a cam carrier bar 111 pivoted at 112 to the frame of the machine whose cam or cam plate 113 is best shown in Fig. 1 in position to engage a pin 114 projecting into its path from the loose 25 clutch member 85, and springs 115, 116 being preferably provided to insure quick and proper positioning of the parts. Thus as soon as the roll 99 has rotated sufficiently in its work of delivering or ejecting the skived 30 blank to swing the arm 104 rearward the clutch is thereby connected so as instantly to start the feeding of the next blank and the raising of the gate 87 and the separation of the rolls 1, 4 to receive said blank. In view of 35 the difference in lengths of different blanks

and other technical requirements of the stock, I have made the free end of the arm 104 adjustable by means of a slot 117 and wing nut 118. If desired also this free end of the arm may depend as shown at 119 in the path of the 70 blank so that if the cam 103 is not used the blank itself will hit the arm or this depending portion 119 thereof and accomplish the tripping of the clutch. The roll 98 is positively driven but as herein shown the roll 99 75 is driven by the engagement therewith of the stock, and is returned to its original position by a spring 120 wound around its farther end, Fig. 1, and secured at one end to the bracket or journal and at the other end to the roll. To 80 insure that the rolls 98, 99 shall invariably grip the work, and bearing in mind that sometimes the front edge of a piece of stock may be slightly thinner than the body of the stock, I have mounted the roll 99 for movement 85 slightly independent of the outgoing pressure gage roll 28. To this end the journal box 121 of the roll 99, see Fig. 3, is mounted for vertical adjustment on the box 27, of the roll 28, being carried in a raceway 122 therein and 90 provided with a stud 123 extending up from the box 121 and limited by a nut 124 in its downward movement and held against said nut yieldingly by a spring 125 within the raceway. This gives a capacity for regulating the tension of the roll 99 and permitting it to be normally slightly nearer the roll 98 than the adjustment of the roll 28 from the skiving knife 31. This construction also gives a capacity for compressing the stock when desirable for certain qualities of blanks. The gate 95 constitutes governing means to control the admission of blanks to the grade detector means and is itself under the control of the above described actuating means. 100

I will now describe the mechanism which adjusts and sets the blank distributor. Pivoted at 126 on the gate is a depending link 127 best shown in Figs. 3 and 15. This link 127 is pivotally connected at 128 to the free 110 end of a bell crank 129 whose lower end 130 engages a pin 131, see Fig. 7, of the detent 132 to hold the same back to the right, Figs. 7 and 15, a spring 133 moving said detent in the opposite direction to engage the locking 115 teeth 18 of the segmental ratchet 16. As the blank gets in position between the feeler or detecting rolls and the latter begin their feeling or thinness-detecting operation the front edge of the blank strikes the upper end 120 of a trip 134, see Figs. 3 and 15 (and corresponding substantially to the finger 46 or to the roll trip 43 of Patent 1,046,213), carried by shaft 135 and normally held towards said rolls by a spring 136, said shaft having an 125 arm 137 connected by a link 138 to lift a depressing arm 139 which is pivoted at 140 to the frame of the machine and normally depresses or holds out of engagement with the teeth 17 the pawl 141, see Fig. 6, said pawl 130

being normally under tendency to move upward by a spring 142. As the work is fed between the detecting rolls 1, 4 and said rolls approach each other in engagement with said 5 work the sector 16 is swung around to the left, Fig. 6 and right or contra-clockwise, Fig. 7 (it being understood that the sector has been moved to the right Fig. 6 or left or clockwise Fig. 7 prior to this time when the rolls 10 1 and 4 were separated) and the successive increments of thinness measurement are preserved by the engagement of the pawl 141 with the teeth 17. Rigid with the sectors 16 and 19 is an arm 143 bifurcated at its free 15 end 144, Fig. 3, to embrace a sleeve 145 and provided with a vertical pin 146 passing through the upper and lower slots 147 in said sleeve. This sleeve at its left has a ratchet 148. A rod 149 reciprocates in said sleeve 20 and is provided on its under side with a notched lock-plate 150, see also Fig. 8, whose righthand end, Fig. 3, constitutes a stop to abut against said sleeve 145, and at its rear end said rod 149 has a rack 151 in engagement with a pinion 152 fast on a post 153 to whose upper end is secured (preferably removably) the chute 102. The pinion 152 and shaft 153 are carried by a housing and bracket 154, see Figs. 2, 3 and 7. A relatively 25 light spring 155 is fastened at one end to a stud 156 on this bracket and at its opposite end to a pin 157 projecting from the rack bar 149. A relatively heavy spring 158 is secured at one end to said pin 157 and at its 30 opposite end to a pin 159 on the sleeve 145. Cooperating with the lock-plate 150 is a dog 160 mounted on a rod 161 and under normal upward impulse by a spring 162, said rod being given vertical movement by a trip bar 35 or unlocking shoe 163, see Figs. 1, 3, 4 and 20, said shoe being mounted at its pivotal end on any convenient member herein shown as loosely mounted on the shaft 135. On the rod 161 is secured a block 164 and here also 40 is preferably a spring 165 for giving further upward impulse or tendency to the rod and all connected parts, said block 164 being engaged on its upper side by the upper end of a hook 166 secured at its lower end to a dog or latch 45 167 in position to engage the ratchet 148. Thus while the top lift or piece of work is being felt of and its determinations transmitted to the sector 16 and adjacent setting mechanism and therefrom to the rack and wedge bar 23, 25, the pin 146 of the arm 143 50 is being simultaneously and similarly adjusted and when finally the gate 87 falls and brings the feeler transmission to a halt by locking said sector by means of its detent 55 132, said pin 146 likewise comes to a halt, thereby preserving the same final thinness-measurement that corresponds to the adjustment of the sector 16. As the latch 167 has been in a raised position out of engagement 60 with the ratchet 148 during this adjustment of said pin 146 it follows that the sleeve 145 has been free to be moved by said pin in case the position in which it was left when the preceding blank was being detected requires said movement. Usually this is the case. The 70 spring 158 always holds the sleeve as far as it can to the left, Figs. 3, 7, and 8. All the adjustment just secured takes place without disturbing the chute 102. When roll 4 is raised, sector 16 is thereby usually swung 75 forward or around to the left, clockwise, Fig. 7, the extent depending upon the grade of blank to which the parts were previously set. As previously set, the sleeve 145 is against the stop or righthand end Fig. 3 of lock-plate 80 150 and the pin 146 is against the righthand end of slot 147. If chute 102 is then at the near side Fig. 1 to deliver a blank into the receptacle 168 for the thinnest blank being handled, say 3-iron, and the succeeding blank 85 proves to be a 3-iron blank the parts will remain unchanged, excepting that the pin 146 will move out to the left in the slot as the roll 4 is raised and will then go back again to its original position. But if the succeeding blank proves to be a thicker blank, say 4-iron, 90 5-iron, or 6-iron (the latter calling for a final positioning of the chute 102 as shown in the drawings) the arm 143 and its pin 146 will be adjusted in the slot 147 to the left Figs. 3 and 95 7, and then when the detent 160 is unlocked from the lock-plate 150 the spring 155 will pull the parts to the left until the righthand end of slot 147 strikes against the pin 146 and is stopped thereby. If however the chute 100 102 is not set for a thin blank but is set for a thick blank, say 9-iron, to deliver into the receptacle 168 at the extreme rear of Fig. 1, and the next blank being detected proves to be a thinner blank, say 6, 7, or 8-iron, the adjusting movement of the arm 143 and pin 146 105 in response to the detection of the feeler mechanism will be to the right Figs. 3 and 7, thereby separating the sleeve from its stop, the pin 146 maintaining continuous engagement with the righthand end of slot 147 and when the detection of said succeeding blank is completed and the arm 143 locked in its adjustment, the unlocking of the detent 160 permits the heavy spring 158 instantly to bring 110 together the sleeve against the stop 150 thereby pulling around to the right the parts 149, 152, 153 and 102 and against the resistance of spring 155. In all cases when the preceding blank has been delivered by the chute to 115 the receptacle for which the chute was set, the lock-plate 150 is disengaged and thereupon the sleeve and stop or righthand end of said lock-plate are brought together by the spring 158, if not already together, and all 120 the connected parts are moved so far as may be required by the new adjustment of the setting mechanism due to the succeeding blank 125 which has meanwhile been felt of, said movement being accomplished by either the spring 130

158 of the spring 155 as just explained, leaving the parts with the pin 146 hard against the righthand end of the slot 147 and the sleeve and stop together. The rod 149 is then 5 locked and so remains until the said next blank for which it has just been set has passed through the evening mechanism and been delivered into its proper receptacle 168. In other words the mechanism is so arranged 10 that said chute is left undisturbed and locked as long as possible so as to be sure to receive and distribute the blank discharged from the rolls 98, 99 before the adjusting operation begins on said chute for the next blank. This 15 construction, therefore, tends to increase the speed that is possible in handling blanks. In other words the succeeding blank is being fed into the machine and its thinness determined and said determinations transmitted and the 20 distributor adjusted in accordance therewith, all excepting the chute, while the preceding blank is being skived and is then being fed out of the machine, discharged, and distributed by the chute. Said chute is under control 25 from said grade determining means but adjusted or set out of time with the latter's adjusting control of the evening mechanism or splitter. Instantly upon the discharge and distribution of the blank by the chute, 30 the succeeding blank comes into contact with the unlocking shoe 163 which through the parts 161 and 160 unlocks the lock-plate 150, whereupon the spring 155 instantly actuates said rack bar and causes the same to rock or rotate the chute in accordance with the position of the pin 146. At the same moment that the dog 160 was moved to unlock 35 said rack bar, the latch 167 was caused to hold the sleeve 145 against movement to the right, although it may move to the left by either the spring 155 or spring 158 as may be required to bring the righthand end of the slot 147 against the pin 146 now stationary in its new adjustment so that by the time 40 the chute 102 has swung to its new position under the influence of one or the other of said springs the parts are practically locked so as to resist the rebound of said chute and hold the same steady in the new adjustment. As 45 soon as the blank which has caused this operation by depressing the shoe 163 passes from said shoe between the rolls 28, 29, the shoe springs up and thereby causes the detent 160 to lock into the lock-plate 150 and thereby hold the chute 102 immovable in its 50 new adjustment while at the same time releasing the sleeve 145 and right hand end of the setting or adjusting mechanism of the distributor so that said mechanism is now 55 free to be adjusted and set again by the next blank to be fed. The feeding of said next blank takes place at about the same instant under the tripping action resulting from the cam 103 of the roll 99 acting through the 60 parts which connect therefrom to the feed-

ing mechanism at the front of the machine. In the Nichols machines the mechanism was required to move back to a given starting point always from whatever adjusted position to which it might previously have been 70 set, whereas here the movement is minimized and is usually simply from one receptacle 168 to the next selected one, and the chute and connected parts do not always have to move back to the front position Fig. 1, and thence 75 swing around each time through a relatively large circuit. In other words, I have provided mechanism which goes from one adjustment to the next and does not have to swing back to a given starting point and then 80 swing from that starting point through the whole range to the next adjustment. This tends materially to aid in increasing the speed or output of the machine. Thus the chute 102 delivers the blank into the selected 85 receptacle 168, Fig. 1, and as the blanks are ejected positively I provide a guard or deflector 169 to prevent their jumping beyond or away from the chute. In some cases, as 90 for chrome leather, it is sometimes desirable that the roll 99 be heated, as by a gas jet 170, Fig. 3.

In operation, let it be supposed that the hopper is filled with top lifts 49, it will be seen 95 that the bottom lift will be held at its opposite sides or edges slightly raised at its rear by the stubby inclines 75 and the rear ends of this lift and adjacent lifts will be out of frictional engagement with the front wall 50 because of the recess 65, so that the projector 100 hook 66 or plate 76 will be sure to engage positively the rear end of the small, thin top lift as it reciprocates forward under the action 105 of its slide 71 and the connected parts 72, 82, 80, 83, 84, etc. Just as the forward end of 110 this top lift nearly reaches the gate 87 the same rotary movement of the shaft 80 which moves the blank projector causes the arm 81 to engage the cam 88, Fig. 2 and Fig. 19, and thereby lift the gate out of the path of the inwardly moving blank. Likewise the top roll 4 is moved upwardly out of the way of the blank, this movement being accomplished 115 through the rotation of the same shaft 80 and the action of its cam 93, see Fig. 14, on the 120 parts 94, 95, 97, and as soon as the leading end of the blank gets just between the rolls 1, 4 the roll 4 closes down tight upon it in 125 feeling position, whereupon, the trip 134 having been actuated, the feeling or detecting operation takes place as in Patent No. 1,046,213, and is transmitted to the central adjusting or setting mechanism 16, 17, 19, and 141 by the connections 10, 11, 12, 13, 14, 15, Figs. 1, 3, 6, 7, and as the blank moves from under the gate 127, 129, 131, 132, and 18, locks the said portion 130 of the setting mechanism in its then adjustment. This adjusting and setting mechanism has set the cam stops 25 thereby controlling 135

the gage roll 28 and hence the splitting operation and has also by reason of the rigid arm 143 adjusted the pin 146 (and usually the sleeve 145) into proper position for the subsequent movement of the distributing chute 102 in accordance with the position of adjustment of the gage mechanism as thus determined by the feeling or detecting operation on the blank. As the rolls 1 and 4 and the chain 2 feed the blank onward the front end of the blank engages the unlocking shoe 163, Figs. 1, 3 and 20, thereby depressing said shoe and through the parts 161, 164, 166, 167, and 148 unlocking the rack bar 149 (by the disengagement of its lock-plate 150 and dog 160) and engaging the sleeve 145 so that the spring 155 instantly swings the chute 102 around to the blank delivering position which corresponds to the thinness determination and setting of the parts thus far explained. The tendency to rebound is prevented by the spring 158 and the ratchet members 148, 167. As the blank continues onward it is engaged between the rolls 28, 29 and skived by the knife 31 being then grabbed by the positively driven roll 98 and the frictionally driven roll 99 and forcibly and positively ejected into the chute 102 to fall into the proper can, bag, or other receptacle 168. While the blank is being ejected the next blank is being fed in and while the first blank is falling and getting into its receptacle the fed in blank is being detected and the detections are being transmitted to the setting mechanism, so that the latter has adjusted the right hand end of the adjusting and controlling mechanism of the distributor by the time it is practicable to adjust the distributor, and then this right hand end of the mechanism which has just been adjusted is locked and the left hand end thereof unlocked so that the two can be brought into complete adjustment by means of the springs 155, 158 and connections. In other words the parts are so coordinated that a maximum economy of time is made possible and therefore a high rate of speed in handling the small pieces of stock results. As the frictionally driven roll 99 is rotated by engagement with the blank being ejected its cam 103 Figs. 1-3, is thereby turned to swing the arm 104 outward and thereby through the connections 105, 106, 107, 108, 111, 113, and 114 release the movable clutch member 85, Figs. 1 and 5, to engage the constantly rotating member 86 and thereby through the parts 84, 85, 81, 82, 72, etc., start the blank feeding mechanism to repeat the cycle of movements already described.

While I have shown my invention applied to a machine especially designed for handling small pieces such as top lifts, heel lifts, taps, half soles and the like, it is not limited thereto as it will be understood that it may readily be changed in dimensions to accommodate soles and other relatively long and

large died-out pieces. Also I wish it understood that many of the separate mechanisms and various sub-combinations and rearrangements of parts as pointed out in the claims are separately within the spirit and scope of my invention and that I am not limited otherwise than defined in the following claims.

My invention is accordingly further described and defined in the form of claims as follows:

1. A machine of the kind described, having means for gaging successive blanks according to their thickness, combined with automatic distributing mechanism for distributing said blanks as gaged, and ejecting rolls for receiving and embracing said blanks from the gaging means and positively grasping and feeding them to the distributing mechanism and deflecting means positioned to insure the ejected blanks arriving properly in said distributing mechanism.

2. A machine of the kind described, having detector means for detecting the grade of successive blanks, an adjustable chute to distribute said blanks in accordance with said detector means, and setting mechanism controlled by said detector means and controlling said chute and constructed and arranged to adjust said chute in accordance with the detected grade of one blank while receiving the detected grade of a succeeding blank from said detector means before said other blank has left said chute.

3. A machine of the kind described, having means for detecting the grade of successive blanks, an adjustable chute to distribute said blanks in accordance with said detecting means, and setting mechanism controlled by said detecting means and controlling said chute, said setting mechanism containing two portions, one of which is capable of responding to said detecting means during the time the other is controlling said chute.

4. A machine of the kind described, having means for gaging successive blanks to detect their thickness-grades, an adjustable chute for distributing the blanks so detected, combined with a two-portion mechanism responsive to said detecting means and governing said chute, one portion controlling the other portion but timed to act dissimultaneously, and locking devices actuated to lock said respective portions alternately.

5. A machine of the kind described, having means for detecting successive blanks according to their thickness, combined with mechanism adjustable through a given range of irons for operating with reference to the detected blanks according to their irons as determined by said detecting means, means for holding said mechanism adjusted for any given iron during the operation thereof with reference to a blank of said given iron, and an adjusting portion adjustable by said detecting means to any given iron ascertained

by said detecting means irrespective of the particular iron to which said adjustable operating mechanism may be held at the time.

6. A machine of the kind described, having, in combination, automatic detecting means for detecting the grade of each of a series of blanks, a plurality of blank-operating mechanisms of different kinds to operate on said series of blanks in accordance with their detected grades respectively, and adjusting mechanism for controlling said operating mechanisms including means for releasing the latter dissimultaneously.

7. A machine of the kind described, having, in combination, automatic means for detecting the grade of each of a series of blanks, a plurality of blank-operating mechanisms to operate on said series of blanks in accordance with their detected grades respectively, and adjusting mechanism for controlling said operating mechanisms including locking mechanism to lock the latter dissimultaneously in their adjustments.

8. A machine of the kind described, having means for gaging successive blanks according to their thickness, combined with automatic distributing mechanism for distributing said blanks as gaged, and including a blank delivering member which is stationary while handling a blank, means for adjusting a portion of said distributing mechanism in accordance with the gaging of a succeeding blank before the preceding blank has been fully distributed by said blank delivering member, and means for bringing said blank delivering member into accord with said adjusted portion after said blank has been delivered by said delivering member and before the latter receives the next blank.

40 9. A machine of the kind described, having means for gaging successive blanks according to their thickness, combined with automatic distributing mechanism for distributing said blanks as gaged, and including a blank delivering member which is stationary while handling a blank, means for so locking said member stationary during its blank handling and delivery, and means for adjusting a portion of said distributing mechanism in accordance with the gaging of a succeeding blank before the preceding blank has been fully distributed by said blank delivering member.

50 10. A machine of the kind described, having means for gaging successive blanks according to their thickness, combined with automatic distributing mechanism for distributing said blanks as gaged, and including a blank delivering member which is stationary while handling a blank, means for adjusting a portion of said distributing mechanism in accordance with the gaging of a succeeding blank before the preceding blank has been fully distributed by said blank delivering member, and means for

bringing said blank delivering member into accord with said adjusted portion after said blank has been delivered by said blank delivering member and before the latter receives the next blank and means for locking 70 said adjusted portion during said bringing into accord of said member.

11. A machine of the kind described, having means for gaging successive blanks according to their thickness, a blank delivering 75 member adjustable to deliver the gaged blanks as gaged but stationary during said delivery, means for controlling the position of said delivering member, and mechanism adjusted by said gaging means for adjusting 80 said controlling means, and timed to adjust said controlling means prior to its controlling action on the delivering member, whereby the latter is undisturbed while delivering a blank during the time said controlling means is being adjusted in accordance with another blank.

12. A machine of the kind described, having means for gaging successive blanks according to their thickness, combined with a 90 blank delivering member to distribute the blanks as gaged, controlling means to set said member to position for so distributing a blank, and adjusting mechanism for adjusting said controlling means according to the 95 gage of successive blanks, said controlling means being operable by said adjusting mechanism while the delivering member is delivering a blank.

13. In a machine of the kind described, 100 blank distributing mechanism consisting of two portions, viz, a delivering member and an adjusting portion, separately adjusted, a spring connecting said two portions, and locking means arranged to hold said delivering member during the blank delivering operation of the latter and thereafter to release said member and permit said spring to move said member in accordance with said adjusting portion.

110 14. In a machine of the kind described, blank distributing mechanism consisting of two portions, viz, a delivering member and an adjusting portion, separately adjusted, a spring connecting said two portions, and locking means arranged to hold said delivering member during the blank delivering operation of the latter and thereafter to release said member and permit said spring to move said member in accordance with said 120 adjusting portion, and a second spring connected to said blank distributing mechanism for moving said delivering member to final adjusted position.

125 15. In a machine of the kind described, blank distributing mechanism consisting of a delivering member and an adjusting portion relatively movable, a spring for connecting said member and portion, a pawl and ratchet for preventing the separation of said member 130

- and portion, a locking device for holding said member immovable, adjusting means for adjusting said portion while said member is held immovable, and mechanism for holding said portion by the engagement of its pawl and ratchet and for unlocking said member to permit its adjustment by said adjusting portion.
16. In a machine of the kind described, a blank distributing mechanism consisting of a delivering member and an adjusting portion relatively movable, a spring for connecting said member and portion, a pawl and ratchet for preventing the separation of said member and portion, a locking device for holding said member immovable, adjusting means for adjusting said portion while said member is held immovable, and mechanism for holding said portion by the engagement of its pawl and ratchet and for unlocking said member to permit its adjustment by said adjusting portion, and a second spring for shifting said member in accordance with its said adjustment.
17. A machine of the kind described, having means for gaging successive blanks according to their thickness, combined with automatic distributing mechanism for distributing said blanks, said distributing mechanism including an adjustable adjusting portion responsive to said gaging means for its adjustment, and a delivering member subject to the control of said adjusting portion but independent of said control during the blank delivering operation of said member, said adjusting portion being constructed to permit its complete adjustment in response to said gaging means irrespective of the position of said delivering member at the time.
18. A machine of the kind described, having means for gaging successive blanks according to their thickness, combined with a delivering member movable through a given range of irons for distributing the gaged blanks according to their irons as determined by said gaging means, means for locking said member for any given iron during the delivery thereof of a blank of said given iron, and an adjusting portion adjustable by said gaging means to any given iron ascertained by said gaging means irrespective of the particular iron to which said delivering member may be locked at the time.
19. A machine of the kind described, having means for gaging successive blanks according to their thickness, combined with automatic distributing mechanism for distributing said blanks as gaged, a gate controlled by the position of a blank for locking said gaging means against further gaging adjustment, and independent tripping means also controlled by the position of a blank for locking and unlocking said distributing mechanism.
20. In a machine of the kind described, detecting means, grading mechanism, and setting mechanism for adjusting and setting said grading mechanism to grade stock in accordance with the determinations of said detecting means, said setting mechanism including means permitting the adjustment of said grading mechanism to take place directly from the position of adjustment for one piece of stock to the position of adjustment for another piece of stock without having first to go back to a standard or predetermined starting point.
21. In a machine of the kind described, a gate and feeding-in devices at the front of the machine, including feeler mechanism adapted to receive and feed the stock to be graded and to detect by continuous act the thinnest spot among a plurality of spots of varying thickness in a leather piece, responsive means for usefully perpetuating or utilizing said grade detection, and intermediate setting mechanism for setting said responsive means in response to said feeler mechanism, and including means permitting the restoration of the gate and feeding-in devices to normal position for receiving a succeeding piece while said responsive means remains set in accordance with the grade detection of the preceding piece.
22. In a machine of the kind described, a gate and feeding-in devices at the front of the machine, including feeler mechanism adapted to receive and feed the stock to be graded and to detect by continuous act the thinnest spot among a plurality of spots of varying thickness in a leather piece, responsive means for usefully perpetuating or utilizing said grade detection, and intermediate setting mechanism for setting said responsive means in response to said feeler mechanism, and including means permitting the restoration of the gate and feeding-in devices to normal position for receiving a succeeding piece while at least a portion of said setting mechanism remains set in accordance with the grade detection for the preceding piece.
23. In a machine of the kind described, a gate and feeding-in devices at the front of the machine including feeler mechanism adapted to receive and feed the stock to be graded and to detect by continuous act the thinnest spot among a plurality of spots of varying thickness in a leather piece, means responsive to said feeler mechanism for utilizing said grade detection, and connecting mechanism permitting the restoration of the gate and feeding-in devices to normal position for receiving another piece while said responsive means remains set in accordance with the grade detection of the preceding piece, and including means for releasing said utilizing means from its said set position separately from the restoration of the feeding-in devices.
24. In a machine of the kind described, detecting mechanism, including a pair of rolls

- which also constitute feeding mechanism, one of said rolls responding to the unevennesses of stock and constituting a feeler roll, said roll having a small diameter with relation to 5 the other roll, a yoke embracing said small roll from end to end of the latter, and means connected with said yoke for transmitting the detecting movement of the small roll.
25. In a machine of the kind described, detecting mechanism, including a pair of rolls which also constitute feeding mechanism, one of said rolls responding to the unevennesses of stock and constituting a feeler roll, said roll having a small diameter with relation to 10 the other roll, a yoke embracing said small roll from end to end of the latter, means connected with said yoke for transmitting the detecting movements of the small roll, and a lifter engaging beneath the ends of said 15 small roll in opposition to said yoke for lifting said small roll and yoke and thereby separating said rolls.
26. A blank sorting machine having, in combination means for measuring a blank, and spring-actuated means automatically responsive to said measuring means for causing the blank to be delivered in accordance with its measurement.
27. A blank sorting machine having, in combination, means for measuring a blank, an adjustable spring-actuated discharge chute adapted to occupy a plurality of operative positions and automatically responsive to the measurements of said measuring means, and means for locking said discharge chute in its adjusted position until the blank for which it is adjusted has been delivered.
28. A blank sorting machine having, in combination, means for measuring a blank, means for subsequently discharging the blank, an adjustable chute for directing its discharge, means for moving the blank from the measuring to the discharging station, automatic means selectively responsive to said measuring means and operative during the movement of the blank from the measuring to the discharging station for adjusting said chute in accordance with the measurement of the blank, and means for locking the chute in its adjusted position until the blank has been discharged.
29. A blank sorting machine having, in combination, means for measuring a blank, an adjustable chute for directing its discharge, means for locking the chute in position temporarily, means responsive to the measurements of said measuring means for storing power while the chute is locked to be subsequently utilized when the chute is 50 unlocked to adjust the chute to its proper delivery position, and means for unlocking the chute to permit its adjustment.
30. A blank sorting machine having, in combination, means for measuring a blank, an adjustable chute adapted to occupy a plurality of operating positions for directing its discharge, and spring actuated means responsive to said measuring means for adjusting said chute from whatever delivery position it occupies to a delivery position corresponding to the measurement of the blank.
31. A blank sorting machine having, in combination, means for measuring a blank, a pivotally mounted chute adapted to occupy a plurality of operating positions for 70 directing its discharge, means responsive to said measuring means for selectively either moving said chute from whatever delivery position it occupies to another delivery position or permitting it to remain in its occupied 75 position, according as the measurement of the blank differs from or conforms to the measurement for which the chute is already positioned.
32. A blank sorting machine having, in combination, means for measuring a blank, an adjustable chute for directing its discharge, means actuated to a definite position dependent upon the measurement of the blank by said measuring mechanism, and delayed means interposed between said last 80 means and said chute for subsequently actuating said chute into a corresponding position for delivering the blank.
33. A blank sorting machine having, in combination, means for measuring a dimension of a blank, means for subsequently discharging the blank, an adjustable chute for directing its discharge, means for advancing the blank after being measured, and automatic means responsive to said measuring means and operative on the advance of the blank through the machine after having been measured, for adjusting said chute in accordance with said measured dimension.
34. A blank sorting machine having, in combination, means for measuring a dimension of a blank, means for subsequently discharging the blank, an adjustable chute for directing its discharge, means for advancing 95 the blank after being measured, automatic means responsive to said measuring means and operative on the advance of the blank through the machine after having been measured, for adjusting said chute in accordance 100 with said measured dimension, and means for thereafter locking the chute in its adjusted position.
35. A blank sorting machine having, in combination, thickness detecting mechanism, blank discharging mechanism, means for sustaining blanks and feeding them to said discharging mechanism, an adjustable chute co-operating with said discharging mechanism movable to guide the blank in a plurality of 110 directions but initially locked against movement, automatic chute actuating means, a controlling device set in response to said thickness detecting mechanism for determining the extent and direction of movement of 115 120
- 60 65 70 75 80 85 90 95 100 105 110 115 120 125 130

said actuating means, means for unlocking the chute after said device has been set to permit an adjustment of the chute as thus determined, and means for re-locking the chute before the measured blank is discharged.

36. A blank sorting machine having, in combination, blank discharging mechanism, means for sustaining and feeding blanks successively to said discharging mechanism, thickness detecting mechanism, an adjustable distributor opposite said discharging mechanism, a movable distributor controlling device the position of which determines the adjustment of the distributor and the actuation of which is responsive to the thickness detecting mechanism, means for locking the distributor against movement after it has been set and until the blank for which it has been set is discharged, and means for unlocking the distributor only after the controlling device has been re-positioned in response to the detected thickness of the succeeding blank.

37. A blank sorting machine having, in combination, a thickness detecting station; a blank discharging station at a point in the machine removed from said thickness detecting station; means for sustaining and feeding at least two blanks between said stations, one blank after the other; an adjustable distributing chute at the discharging station; chute controlling mechanism at the thickness detecting station responsive to the detected thickness of the first blank passing therethrough for determining the position of said chute; means for locking the chute in its adjusted position before said first blank is discharged and subsequently restoring said chute controlling mechanism to its normal position whereby it may respond to the detected thickness of the succeeding blank; and means for unlocking the chute after each setting of said controlling mechanism.

38. A blank sorting machine having, in combination, means for measuring a blank, means adapted to occupy a plurality of operating positions for directing its discharge, and normally idle actuating means set in response to the measuring means for subsequently positioning said directing means to deliver the blank in accordance with its measurement.

39. A blank sorting machine having, in combination, means for measuring a blank, an adjustable chute for directing its discharge, a plurality of springs for actuating said chute in one direction or the other, and automatic means responsive to said measuring means for adjusting one of said springs to cause the chute to be adjusted to deliver the blank according to its measurement.

40. A blank sorting machine having, in combination, means for measuring a blank, an adjustable chute adapted to occupy a plurality of operating positions for directing

its discharge, spring actuated mechanism co-operating with said chute, and automatic means responsive to said measuring means for causing said mechanism to actuate said chute into a position corresponding to the measurement of the blank.

41. A blank sorting machine having, in combination, means for measuring a blank, a pivotally mounted chute adapted to occupy a plurality of operating positions for directing its discharge, means responsive to said measuring means and comprising springs for adjusting the position of said chute in accordance with the measurement of the blank, and means for locking the chute in its adjusted position.

42. A blank sorting machine having, in combination, means for measuring a blank, an adjustable chute adapted to occupy a plurality of operating positions for directing its discharge, spring actuated mechanism for adjusting the chute, means for locking the chute in adjusted position, means responsive to said measuring means for varying the power condition of one of said springs while the chute is locked, and means for releasing said locking means to permit such spring to actuate said chute into a delivery position corresponding to the measurement of the blank.

43. In a machine of the kind described, in combination, automatic detecting means for detecting the grade of each of a series of blanks, a plurality of grading mechanisms operative with relation to said series of blanks in accordance with their detected grades respectively, and adjusting mechanism for controlling said grading mechanisms including means for adjusting and locking one of said grading mechanisms and then adjusting another of said grading mechanisms.

44. In a machine of the kind described, in combination, mechanisms for splitting and sorting a series of blanks, and automatic mechanism controlled by each blank presented to the machine for dissimultaneously governing and locking the said splitting and sorting mechanisms.

45. In a machine of the kind described, two graders, of which one is an automatic distributing mechanism, both actuated in accordance with the thickness of each blank, said distributing mechanism including a movable blank distributing chute automatically rotatable to different predetermined delivering positions, together with means to temporarily lock said chute in moved position, means to temporarily lock said other grader during its grading, and means for setting said other grader and distributing mechanism including means for actuating said locks to locking position dissimultaneously.

46. In a machine of the kind described, two graders, one of which includes a pair of feed rolls and the other of which includes an ad-

justable distributor chute, both graders being actuated in accordance with the thickness of each blank, and a pair of delivering rolls adapted to receive a blank from said feed rolls and deliver it to the distributor chute.

47. A machine of the kind described, having means for gaging successive blanks according to their thickness, a blank distributor responsive to the gaging means, and means responsive to the blanks after they leave the gaging means and before they leave the distributor for starting said gaging means.

10 48. A machine of the kind described, having means for gaging successive blanks according to their thickness, a blank distributor responsive to the gaging means, a gate for controlling the operation of the gaging means and a trip and connections therefrom to the gate adapted to be actuated by a blank before it leaves the distributor for controlling the gate.

15 49. A machine of the kind described, having means for gaging successive blanks according to their thickness, including upper and lower members adapted to receive the blanks between them for detecting their thicknesses, a blank distributor responsive to the gaging means, and a trip and connections therefrom to the gaging means adapted to be

actuated by a blank before it leaves the distributor for separating said members to receive a blank. 30

50. A machine of the kind described, having means for gaging successive blanks according to their thickness, grading mechanism responsive to said gaging means, and means adapted to be actuated by a blank for starting the gaging means. 35

51. A machine of the kind described, having means for gaging successive blanks according to their thickness, grading mechanism responsive to said gaging means, a gate for controlling the operation of the gaging means, and means adapted to be actuated by a blank after it has left the gaging means for 40 controlling the gate. 45

52. A machine of the kind described, having means for gaging successive blanks according to their thickness, including upper and lower members adapted to receive blanks 50 between them for detecting their thicknesses, grading mechanism responsive to said gaging means, and means adapted to be actuated by a blank after it has left the gaging means for separating said members to receive a blank. 55

In testimony whereof, I have signed my name to this specification.

LEANDER A. COGSWELL.

CERTIFICATE OF CORRECTION.

Patent No. 1,693,638.

Granted December 4, 1928, to

LEANDER A. COGSWELL.

It is hereby certified that error appears in the printed specification of the above numbered patent requiring correction as follows: Page 14, line 37, claim 50, after the word "blank" insert the words "after it has left the gaging means"; and that the said Letters Patent should be read with this correction therein that the same may conform to the record of the case in the Patent Office.

Signed and sealed this 8th day of January, A. D. 1929.

M. J. Moore,
Acting Commissioner of Patents.

justable distributor chute, both graders being actuated in accordance with the thickness of each blank, and a pair of delivering rolls adapted to receive a blank from said feed rolls and deliver it to the distributor chute.

47. A machine of the kind described, having means for gaging successive blanks according to their thickness, a blank distributor responsive to the gaging means, and means responsive to the blanks after they leave the gaging means and before they leave the distributor for starting said gaging means.

10 48. A machine of the kind described, having means for gaging successive blanks according to their thickness, a blank distributor responsive to the gaging means, a gate for controlling the operation of the gaging means and a trip and connections therefrom to the gate adapted to be actuated by a blank before it leaves the distributor for controlling the gate.

15 49. A machine of the kind described, having means for gaging successive blanks according to their thickness, including upper and lower members adapted to receive the blanks between them for detecting their thicknesses, a blank distributor responsive to the gaging means, and a trip and connections therefrom to the gaging means adapted to be

actuated by a blank before it leaves the distributor for separating said members to receive a blank. 30

50. A machine of the kind described, having means for gaging successive blanks according to their thickness, grading mechanism responsive to said gaging means, and means adapted to be actuated by a blank for starting the gaging means. 35

51. A machine of the kind described, having means for gaging successive blanks according to their thickness, grading mechanism responsive to said gaging means, a gate for controlling the operation of the gaging means, and means adapted to be actuated by a blank after it has left the gaging means for 40 controlling the gate. 45

52. A machine of the kind described, having means for gaging successive blanks according to their thickness, including upper and lower members adapted to receive blanks 50 between them for detecting their thicknesses, grading mechanism responsive to said gaging means, and means adapted to be actuated by a blank after it has left the gaging means for separating said members to receive a blank. 55

In testimony whereof, I have signed my name to this specification.
